(57) **CLAIM**

The ornamental design for a low profile gearcover, as shown and described.

DESCRIPTION

FIG. 1 is a front perspective view of a low profile gearcover according to the principles of the present invention.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1; and,

FIG. 7 is a bottom plan view of FIG. 1.

The present application is directed to the design illustrated in the drawings. The features shown in broken lines are for illustrative purposes only and form no part of the claimed design.
